UNITED STATES PATENT OFFICE

HEINZ WENDTLAND, OF ALTONA-ON-THE-ELBE, GERMANY

WATER LOCK FOR ACETYLENE GENERATORS

Application filed August 3, 1931, Serial No. 554,765, and in Germany November 18, 1929.

I have filed applications in Germany on the 18th November, 1929 (patent not yet granted) and on the 7th April, 1931; and in Great Britain on the 13th March, 1931.

5 The present invention relates to acetylene generators more particularly to the water locks of such generators which as is well known, are interposed between the acetylene generator proper and the point of consumption, for instance, the pipe leading to the burners. The object of the invention is to provide for increased safety against a dangerous backflow of gas or oxygen through the water lock to the acetylene generator. With this object in view, the invention consists in the provision between the water lock and the acetylene generator of an un-enclosed free standing safety or compensating receiver into which the water of the water lock is forced back whenever a back pressure occurs. Owing to the provision of this compensating or safety receiver the water of the water lock cannot escape whenever a backflow occurs owing to the 15 back pressure and consequently the water cannot be forced into the purifier or the acetylene generator proper. The safety container is of sufficient capacity to receive the whole of the water of the water lock.

20 As soon as the disturbance caused by back pressure has disappeared, the pressure of the acetylene gas forces the water back into the lock. The water lock and the safety receiver are preferably made of the same shape and are preferably made tubular, the proportion of the diameter to the length of the vessel being in each case 1:6. In the piping between the water lock and the safety receiver may be provided a nonreturn valve 25 if needed. With a sufficiently high gas pressure, this return valve may be dispensed with.

30 It may be pointed out that the return valve does not by itself afford any safety 35 against backflow of the water from the lock towards the acetylene generator when a back pressure occurs, as the inertia of the valve cone is too high to enable the valve to act with sufficient rapidity. Moreover, the 40 said valves are always liable to become

leaky and are therefore not quite reliable in action.

The accompanying drawing shows, by way of example, three constructions embodying the features of the invention. 55

Fig. 1 shows one construction of the improved water lock in sectional elevation in the normal working condition of the apparatus.

Fig. 2 shows the same construction after a 60 backflow of the water has occurred owing to back pressure.

Fig. 3 shows in sectional elevation a simplified construction in the normal working condition of the water lock, and Fig. 4 is a 65 sectional elevation corresponding to Fig. 3 showing the water forced back into the safety container.

Fig. 5 shows in sectional elevation a construction in which the water lock is arranged above the safety receiver. 70

A water lock container *a* is provided in usual manner with a water lever control valve *b*, a gas delivery valve *c*, a filling opening *d* which is closed in known manner by means of a metal diaphragm designed to burst at a certain maximum interior excess pressure. In the bottom of the container *a* is provided a gas inlet valve *e* which controls the opening of a pipe *f* connecting the bottom of the container *a* with the bottom of the safety or compensating container *g*. The container *g* is provided with a gas inlet pipe *h* which projects from the top of the container *g* into its interior. The exit opening of the pipe *h* is controlled by a float operated valve *i*, this valve being always open during normal operation. In the construction shown in Figs. 3 and 4 the float valve *i* is omitted and the gas inlet pipe *h* does not project into the interior of the 75 container *g*. 80

In the construction shown in Fig. 5, the safety container *g* is arranged above the water lock container *a* and there is no float valve in the safety container. 85

The operation is as follows:—

Should any explosive gas mixture flow back through the delivery valve *c* into the container *a*, a part or the whole of the water 90

95

100

contained in the container *a* will flow through the valve *e* into the container *g*. This is due to the fact that during the normal operation of the apparatus, the valve *e* is always moving and consequently is unable to stop backflow of the water whenever a back pressure suddenly occurs. Experience shows that whenever a rapid back pressure occurs a substantial amount of water will 10 pass through the valve *e*. It will be understood that a flame cannot flash back through the water into the container *g* and thus endanger the acetylene generator.

As soon as, after a back flash, the burner 15 is opened again, the mixture which has collected in the water lock container escapes first, and the water is then forced back from the safety container into the water lock so that the latter will again work with the 20 required water level.

The provision of the safety container *g* absolutely prevents water reaching the pipe *h*. Should, in the construction according to Figs. 3, 4 or 5, owing to an accident, a 25 substantial quantity of oxygen be forced through the water lock into the acetylene generator, there will be no danger of explosion, as the mixture formed will be innocuous and will immediately after the removal of the disturbing factors flow back 30 into the water lock and escape therefrom. It will thus be seen that any back pressure caused by an explosion can never become dangerous, as the water lock will always contain water, there being no possibility of the water being entirely forced out and lost.

Another advantage is due to the fact that any damage or deformation of the apparatus 40 will be immediately noticeable owing to the fact that the containers stand entirely free and are easy of access and inspection. Water locks having telescopically arranged tubes or pipes do not present this advantage.

The present application is a continuation 45 in part of my co-pending patent application, Serial No. 531,139 filed on the 18th April, 1931.

I claim:

1. A water lock for acetylene generators, 50 comprising in combination: a closed container which is normally partly filled with water and is provided with a gas delivery port arranged above the water level, said container constituting the water lock proper; 55 a second closed container which is normally empty; and a pipe connected at one end to the bottom of said first named container and at the other end to the bottom of said second container, said second container being provided with an inlet for gas and being adapted 60 to receive water displaced by a back pressure from said first named container, substantially as described.

2. A water lock for acetylene generators, 65 comprising in combination: a first container

which, during normal working operations, is always partly filled with water forming the water lock, and is provided at its top with a gas delivery valve and at its bottom with a non-return valve; a second container which is of approximately the same volume as said first container and is empty during normal working operations; a pipe connected at one end to the bottom of said first named container and at the other end to the bottom of said second container; a gas inlet pipe leading from the top into said second container; and a float controlled valve for controlling said gas inlet pipe, whereby water displaced by back pressure from said first named container is prevented from entering the gas inlet pipe of said second container, substantially as described.

3. A water lock for acetylene generators, 70 comprising in combination: a first container, which, during normal working operations is always partly filled with water forming the water lock; a gas delivery valve at the top of said container; a non-return valve in the bottom of said container; a second container which is of approximately the same volume as the first container and is empty during 75 normal working operations; a communication pipe connected at one end to the bottom of one of said containers and at the other end to the bottom of the other container; a gas inlet pipe leading from the top of the second container into the interior of said container; and float controlled valve means for controlling the lower end of said gas inlet pipe, substantially as described.

4. A water lock for acetylene generators, 80 comprising in combination: a first container which, during normal working operations is always partly filled with water forming the water lock; a gas delivery valve at the top of said container; a non-return valve in the bottom of said container; a second container which is of approximately the same 85 volume as the first container and is empty during normal working operations; a communication pipe connected at one end to the bottom of said first named container and at the other end to the bottom of said second container; a gas inlet pipe leading from the top of the second container into the interior of said container; float controlled valve means for controlling the lower end of said gas inlet pipe, substantially as described.

5. A water lock for acetylene generators, 90 comprising in combination: a first vertical tubular container which, during normal working operations is always partly filled with water; a gas delivery valve arranged at the top of said container; a closable filling opening at the top of said container closed by means of a safety diaphragm; a check valve on said container for checking the wa- 95

ter level; a non-return water valve in the bottom of said container; a second vertical tubular container which is arranged by the side of the first named container and is empty during normal working operations, said second container having approximately the same volume as said first named container; a communication pipe connected at one end to the bottom of said first named container and at the other end to the bottom of said second container; a gas inlet pipe passing from the top of the second container into the interior, the lower end of the pipe being located approximately at the same level as the water level in the first container; and float controlled valve means for closing the lower end of said gas inlet pipe, substantially as described.

6. A water lock for acetylene generators, comprising in combination: a water lock container which, during normal working operations is always partly filled with water; means for delivering gas from said container located above the water level; a second container which is of approximately the same volume as said first container and is empty during normal working operations; means for admitting gas to the top of said second container; a communication pipe connected at one end to the lower portion of said water lock container and at the other end to the lower portion of said second container; and a non-return valve in the bottom of said first container, substantially as described.

7. A water lock for acetylene generators, comprising in combination: a tubular water lock container which, during normal working operations is always partly filled with water; a gas exit arranged above the water level in said container; a second tubular container which is arranged above said first named container and is empty during normal working operations, said second container having approximately the same volume as said water lock container; a communication pipe connected at one end to the bottom of said water lock container and at the other end to the bottom of said second container; a gas inlet arranged in the upper portion of said second container, and a non-return valve arranged in the bottom of the first container, substantially as described.

55 Signed at Hamburg, Germany, this 20th day of July 1931.

HEINZ WENDTLAND.
